ARTHUR MÜLLER, OF BERN, SWITZERLAND.

CLASSING CLAMP.

Application filed December 5, 1927, Serial No. 237,974, and in Belgium July 26, 1927.

The present invention relates to a classing-clamp for file-papers of the kind where lateral lugs formed on a rigid strip represent the stationary paws of clamps having movable paws cooperating with the stationary paws and constituted of curved flat springs secured to the ends of resilient strips and pressed down unto the stationary paws by means of hand operated slides guided within said rigid strip.

The classing clamps of this kind known heretofore did not give entire satisfaction because the grip of the two paws was not safe enough.

In the clamp according to the present invention one of the paws possesses at least two parallel ridges arranged so that in the closed position of the clamp the working edge of the movable paw engages the stationary paw exactly in the space left between the ends of the said ridges and the bent-up working edge of the stationary paw with a view of bending the paper in an undulated form. This bending prevents any displacement of the clamped papers by some casual tractive effort.

The annexed drawing represents as an example one working form of the invention.

Fig. 1 is a perspective view of the whole and

Figs. 2 and 3 are the first a longitudinal section of the closed clamp and the second a cross-section through a manually operated clamp.

According to the drawing a rigid strip 1 is provided with bent-up longitudinal edges 2 forming a groove and with two lateral lugs 3 representing the stationary paws of clamps. These lugs have two parallel ridges 4 obtained by pressing the metal. The movable paws of the clamps are constituted of curved flat springs 6 riveted to the free ends of a springy strip 7 fixed at its middle part 8 to the strip 1. The flat spring 7 is bent in such a way that its two free arms have the tendency to stand up. These ends are bent down so as to close the clamps by sliding the

buttons 9 in the groove of the strip 1. The upper surface of these buttons is roughened at 10 so as to afford a good hold for the fingers.

The outer edges 5 of the stationary paws 3 of the rigid strip 1 are bent-up as shown in Fig. 2. In the closed position of the clamps the working edge of the movable paw bears 55 on the space left between the ends of the ridges 4 and the bent-up edge of the stationary paw.

If it is desired to put into the classing clamp some new file-papers, the two buttons 60 9 are pushed close up to part 8 whereupon the arms of the springy strip 7 will stand up and the clamps be opened. The paper is now laid in upon the stationary paws 3 and the two buttons pushed asunder up to the ends 65 of the rigid strip. Then the working edges of the movable jaws will bear on the paper and bend it in an undulated form so as to hold it firmly.

As means for fixing the rigid strip of the 70 classing-clamp to the wrapper of a file-book there are rivets fixed at the holes 11 shown in Fig. 1.

What I claim as new is:

In a classing clamp for file papers adapted 75 to be fastened to a cover board and in combination, a rigid metallic strip provided at the ends with two lateral lugs and having bent-up lateral edges forming grooves, a resilient strip attached to the middle portion 80 of the rigid strip and having both its ends bent-up between the grooves of the rigid strip, curved flat springs riveted to the up standing ends of this resilient strip and extended sideways so as to match with the 85 lateral lugs of the rigid strip with a view of forming clamps, and rectangular buttons arranged slidably within said grooves and above each of the up-standing legs of the resilient strip and having a roughened surface so as to present a safe grip when being operated.

In testimony whereof I affix my signature.

ARTHUR MÜLLER.
